CLAIM

The ornamental design for a chilled beam, as shown and described.

DESCRIPTION

FIG. 1 is an isometric view of a first embodiment of a chilled beam;

FIG. 2 is a side view thereof;

FIG. 3 is another side view thereof;

FIG. 4 is an end view thereof;

FIG. 5 is another end view thereof;

FIG. 6 is top view thereof;

FIG. 7 is a bottom view thereof; and,

FIG. 8 is an isometric view of a second embodiment of the chilled beam.

The broken lines in the drawings illustrate the environment of the chilled beam which forms no part of the claimed design.

The break lines indicate that the appearance of any portion of the chilled beam between the break lines forms no part of the claimed design.
